US00D798842S

(12) **United States Design Patent** (10) **Patent No.:** **US D798,842 S**
(45) **Date of Patent:** **** Oct. 3, 2017**

(54) **REMOTE CONTROL HOUSING**

(71) Applicant: **Hunter Douglas Inc.**, Pearl River, NY (US)

(72) Inventors: **Ronald R. Kass**, New York, NY (US); **Douglas J. Barr**, Broomfield, CO (US); **Joseph E. Kovach**, Brighton, CO (US); **Kevin M. Dann**, Englewood, CO (US); **David J. Parrett**, Louisville, CO (US); **Clark Brace**, Westminster, CO (US); **Fred Bould**, Menlo Park, CA (US); **Jaime Caso**, Redwood City, CA (US)

(73) Assignee: **HUNTER DOUGLAS, INC.**, Pearl River, NY (US)

(**) Term: **15 Years**

(21) Appl. No.: **29/577,436**

(22) Filed: **Sep. 13, 2016**

(57) **CLAIM**

We claim the ornamental design for a remote control housing, as shown and described.

DESCRIPTION

FIG. 1 is a top front isometric view of a first embodiment of a remote control housing in accordance with the present design.

FIG. 2 is a front elevation view of the remote control housing of FIG. 1.

FIG. 3 is a rear elevation view of the remote control housing of FIG. 1.

FIG. 4 is a right side elevation view of the remote control housing of FIG. 1.

FIG. 5 is a left side elevation view of the remote control housing of FIG. 1.

FIG. 6 is a top plan view of the remote control housing of FIG. 1; and,

FIG. 7 is a bottom plan view of the remote control housing of FIG. 1.

The broken lines illustrate portions of the remote control housing that form no part of the claimed design.
